UNITED STATES PATENT OFFICE

2,522,126

LUGGAGE CASE WITH TISSUE-DISPENSING CONTAINER

Henry L. Kotkins, Seattle, Wash.

Application September 30, 1948, Serial No. 51,921

2 Claims. (Cl. 190—42)

1

This invention relates to a luggage case. More specifically, the invention relates to a luggage case which has a convenient container on the inside thereof for dispensing cleansing tissues.

It is an object of this invention to provide a luggage case with a container inside especially arranged for dispensing cleansing tissues.

It is another object of this invention to provide a luggage case in which a combination of a cleansing tissue container and a cosmetic container is conveniently located.

A still further object of this invention is to provide a molded plastic container for cleansing tissues for use in a luggage case.

A still further object of this invention is to provide a molded plastic container with an elongated slot in the bottom thereof for dispensing cleansing tissues together with a cosmetic container with a bottom substantially coextensive with the top of the tissue dispensing container whereby the bottom of the cosmetic container serves to close off the tissue container.

Other objects of this invention will more fully appear in the following detailed description taken in connection with the accompanying drawing which illustrates a single embodiment thereof, and in which:

Figure 1 is a perspective view of a traveling case showing the cosmetic container in place;

Figure 2 is a broken sectional view of the case of Figure 1 illustrating, in an enlarged form, the tissue dispensing tray and cosmetic tray; and

Figure 3 is an inverted plan view of the tissue dispensing tray showing the elongated slot through which cleansing tissues may be drawn.

As shown on the drawings:

The case illustrated in Figure 1 is of the small, "week-end" or cosmetic case type. It consists of a box 10 with a hinged top 11 and lock clasps 12. The case may be made of plywood or similar materials which have a high ratio of strength to weight. The rigid material in the case is preferably covered by a coated or lacquered waterproof fabric for the sake of appearance and also for protection of the case. Leather may also be used for this purpose.

On the interior of the case a tray or container 13 is located as shown in Figure 2. The container 13 has an elongated slot 13a in the bottom thereof disposed for dispensing cleansing tissues of the type obtainable at drug and grocery stores. The center of the slot may be widened as at 13b in order to facilitate the handling of the tissues. The container 13 may be made of a molded plastic such as styrene and it is advisable

2

that the container be transparent in order that a shortage of the cleansing tissues may be revealed. Non-transparent plastic such as hard rubber or Bakelite may, however, be used.

The container 13 is maintained in position by an angle support member 14 attached to the box 10. A container or tray 15 substantially co-dimensional with the container 13 provides space for keeping cosmetics, etc. A bottom portion 15b of the container 15 is disposed to fit the top perimeter 13c of the container 13 whereby the bottom of the container 15 serves as a means for closing the container 13. Both containers 13 and 15 form a unit which has one outside dimension substantially coextensive with one of the inside dimensions of the box 10. The support member 14 maintains the containers 13 and 15 far enough above the bottom of the case to enable the top 11 to function as a closure means for the container 15. In this fashion the cosmetic container 15 is exposed upon opening the top 11 and yet with the top 11 closed the cosmetics will stay inside of the container 15 even though the case is turned upside down.

During use, the package of cleansing tissues is placed in the container 13 with the withdrawal slot facing the slot 13a. The container 15 is then put in place and the combination is ready for use. To obtain a cleansing tissue it is only necessary to open the top 11 and reach underneath the container 13 and withdraw a cleansing tissue through the slot 13a.

It is readily apparent that if additional tray capacity is not desired, the tray 15 can function solely as a closure for the tray 13 rather than as a tray and a closure as shown in Figure 2.

It will, of course, be understood that various details of the construction may be varied through a wide range without departing from the principles of this invention and it is, therefore, not the purpose to limit the patent granted hereon otherwise than necessitated by the scope of the appended claims.

I claim as my invention:

1. A device for carrying luggage comprising a box including bottom, side and end walls, and having a top which may be opened, means for securing said top in closed position, a first molded plastic container, means to support said first container interiorly of said box and in spaced relation to said bottom wall, said first container having one of its outside transverse dimensions substantially less than a corresponding inside transverse dimension of said box to space said first container from one of said side or end walls, said

first container having an elongated slot in the bottom thereof through which cleansing tissues may be dispensed, a second container of about the same dimensions as the first container and supported by the first container so that the bottom of the second container serves as a top for the first container, and said support means maintaining said second container in position to be closed by the top of said box when said top is closed, and the spaced relation of said first container with the bottom wall of said box and with one of said side or end walls providing access to said dispensing slot without disturbing the position of either of said containers.

2. A device for carrying luggage comprising a box including bottom, side and end walls, and having a top which may be opened, means for securing said top in closed position, a container, means stationarily supporting said container interiorly of said box and in spaced relation to said bottom wall, said container having one of its outside transverse dimensions substantially less than a corresponding inside transverse dimension of said box to space said container from one of said

side or end walls, said container having an elongated slot in the bottom thereof through which cleansing tissues may be dispensed, and a closure disposed over the top of said container, said support means maintaining the spaced relation of said container with the bottom wall of said box and with one of said side or end walls to provide access to said dispensing slot without disturbing the position of said container and without removing said closure.

HENRY L. KOTKINS.
